HARRY C. FRICKE AND GEORGE E. TURNER, OF PITTSBURG, PENNSYLVANIA, ASSIGNORS
TO TURNER-FRICKE MANUFACTURING COMPANY, OF PITTSBURG, PENNSYLVANIA.

MIXING-VALVE FOR EXPLOSIVE-ENGINES.

No. 882,939.

Specification of Letters Patent. Patented March 24, 1908.

Application filed July 30, 1907. Serial No. 386,218.

To all whom it may concern:

Be it known that we, HARRY C. FRICKE and GEORGE E. TURNER, citizens of the United States, residing at Pittsburg, in the county of Allegheny and State of Pennsylvania, have invented certain new and useful Improvements in Mixing-Valves for Explosive-Engines; and we do hereby declare the following to be a full, clear, and exact description of the invention, such as will enable others skilled in the art to which it appertains to make and use the same.

Our invention consists in the novel features hereinafter described reference being had to the accompanying drawings which illustrate one form in which we have contemplated embodying our invention and the invention is fully disclosed in the following description and claims.

20 In the construction and operation of mixing valves for explosive engines, or internal combustion engines, much difficulty has been experienced in obtaining a thorough and desired mixing of the air with the gas or other fuel constituent to form the explosive mixture supplied to the cylinders.

The objects of our invention are to secure a better and more uniform mixing of the fuel constituent and air, while maintaining the proper proportions, regulating the quantity of fuel and air by means of a governor and also to simplify the construction and arrangement of the valve mechanism, so that it can be opened and the working parts removed conveniently and expeditiously.

40 In carrying out our invention to secure the desired mixing of the gas or fuel and air, we arrange the inlet for the fuel preferably in a direct line with the outlet for the mixture and provide apertures for admitting the air on opposite sides of the full inlet and in close proximity thereto, so that as the fuel is drawn in by the suction of the engine, the air to be mixed therewith will be drawn in 45 equally on opposite sides, and mixed intimately with the fuel, which may be either natural or artificial gas, or carbureted air or hydrocarbon vapor.

50 Referring to the accompanying drawings, Figure 1 represents a three cylinder explosive or internal combustion engine having our improved mixing valve applied thereto and connected with a centrifugal governor operated by the engine. Fig. 2 is a horizon-

tal sectional view through the mixing valve, drawn to an enlarged scale. Fig. 3 is a vertical sectional view of the valve also drawn to an enlarged scale.

In the drawings A, A, A represent the power cylinders of a gas or other explosive engine, and B represents a manifold or pipe communicating with each of said cylinders, extending preferably horizontally in a straight line, and closed at one end as indicated at b. The opposite end of the manifold is connected with our improved mixing valve, which is preferably constructed and arranged as shown in the accompanying drawings.

C represents the outer casing of the valve which is bored out vertically to form a cylindrical chamber, and is provided with an outlet aperture c from said chamber discharging directly into the end of the manifold B, and the valve casing is secured to the manifold in any desired manner as by screws b', as indicated in the drawing, thus supporting the valve in position on the engine.

The cylindrical wall of the casing C is also provided with one, two or more fuel inlet openings or ports c' c' (two being shown) which are in the form of rectangular slits or slots and are located opposite the center of the outlet aperture c. Fuel, such as artificial or natural gas, hydrocarbon vapor, or carbureted air is admitted to the said inlet aperture or apertures, in any desired way. In this instance the casing is shown provided with a recess outside of said apertures, having a flanged plate c' secured to its walls, said plate being provided with an internally threaded aperture c' in axial alignment with the outlet aperture c, for the reception of a pipe for conveying the fuel from a suitable source. Where gas is employed, it is admitted preferably at atmospheric pressure, a pressure regulating device (not shown) being employed to maintain the uniform pressure of the gas, in a well known manner.

The valve casing C is also provided with air inlet ports or apertures c' c', which are located on opposite sides of the fuel inlet port or ports, and in such positions that a line connecting the centers of the opposite air ports will be perpendicular or substantially perpendicular to a line through the horizontal centers of the gas ports and the outlet aperture, as clearly indicated in Fig. 2 by dotted lines. We prefer that the oppo-

site air ports shall be so arranged with respect to the gas ports that the air will enter the valve from both sides at an angle of substantially 90° to the direction in which the 5 gas enters, as shown in the drawings, but we do not limit ourselves to this exact construction, as the air ports may be formed nearer to or further away from the gas ports than there shown, if desired, but in all cases 10 the air ports should be on opposite sides of the gas ports and substantially equi-distant therefrom.

D represents the valve which is in the form of a hollow cylinder, preferably closed at top 15 and bottom and having gas ports d', d' and adapted to register both horizontally and vertically with the gas ports c', c' in the casing, air ports d^4, d^4 , adapted to register vertically with, but of greater length horizontally 20 than the air ports, and an outlet aperture d communicating with the outlet aperture c in the casing and large enough for the passage of the largest quantity of the explosive mixture which is required to pass therethrough. 25 From this construction it follows that a horizontal rotary movement of the valve, (supposing the gas ports of valve and casing to be in registration) will cause the gas ports to be partly cut off without affecting the air ports, 30 thereby effecting a reduction in the proportion of gas or fuel to air, in the resulting mixture, while the vertical movement of the valve will cut off the supply of both air and gas or fuel more or less without affecting the 35 proportions thereof in the mixture. The horizontal rotary movement of the valve is designed to be accomplished by hand adjustment and the vertical movement by the action of a centrifugal governor, as herein- 40 after described.

The valve D is mounted rotatably on a valve rod D' which has a portion d^5 of reduced diameter passing through central apertures in the heads of the valve, forming a 45 shoulder d^6 below the valve, and a nut or nuts d^7 on the upper threaded end of the part d^5 , secures the valve firmly to the rod, while permitting the valve to be rotated slightly in either direction with respect to the rod.

50 The casing C is provided with a rotary bottom plate c^5 held in place by a ring c^6 secured to the casing, and said bottom plate has a central aperture for the passage of valve rod D', and a sleeve c^7 depending from the bottom plate and coaxial with said aperture, the lower end of the sleeve being internally threaded.

The valve rod D' is provided within the upper part of sleeve c^7 with a collar d^8 , secured to the rod, and a counterbalance spring E engages said collar, at its upper end and has its lower end supported by an adjustable hollow plug c^8 screwed into the lower end of said sleeve and provided with a 60 jam nut c^9 . This spring is so adjusted as to

compensate for the weight of the valve and rod and render the action of the governor more sensitive and accurate. The valve may, however, be counterbalanced in other ways if desired.

70 c^{14} represents a top plate or cap for closing the upper end of the casing, which is held in place by suitable screws. By the simple removal of this plate and the nuts d^7 , the valve may be lifted out for inspection or repair.

75 The position of the valve, with respect to its vertical axis is determined by the following devices. The bottom plate c^5 is provided with a vertically disposed pin c^{10} and extending through an aperture in the bottom of the valve, in which it has a sliding engagement. The bottom plate c^5 is provided with a hand lever c^{11} for adjusting it rotatably, which in this instance is a separate piece having a circular aperture in one end fitting around the 80 sleeve c^7 , and a hole through which the lower portion of the pin c^{10} extends. Said hand lever is also provided with a clamping surface c^{12} to engage the stationary ring c^6 . A thumb nut c^{13} is screwed on the lower end of 85 the pin c^{10} and when this nut is turned up the clamping face c^{12} of the lever is forced against the ring c^6 , thus holding the rotatable bottom plate c^5 and pin c^{10} in their adjusted positions. Obviously, to adjust the valve rotatably to 90 diminish or increase the proportion of gas or fuel in the mixture, it is only necessary to loosen nut c^{13} and move lever c^{11} in one direction or the other, and then set up nut c^{13} , and this can be done while the engine is running. 95 The sliding engagement of the pin c^{10} and the valve, will permit the vertical movements of the valve under the action of the governor in whatever position the valve may be set. The lower end of valve rod D' is connected 100 to a pivoted lever F with the governor G, as indicated in the drawings, so that the areas of the air and gas ports are increased and diminished by the governor, in accordance with the load requirements of the engine, and without affecting the predetermined proportions of fuel and air in the mixture. The connection between the valve rod D' and the governor, is preferably such 105 as will prevent the rod from turning when the valve proper is rotated on the rod in effecting such occasional adjustments as may be necessary.

110 During the suction stroke of any one of the engine cylinders the gas or fuel is drawn in through the fuel inlet ports and air is drawn in on opposite sides of the stream of gas, both air and gas passing in a straight line through the outlet aperture and causing the gas and air to combine very much in the same manner as in a Bunsen burner, and producing a very uniform and satisfactory mixture. The proportions of the mixture as 115 previously explained are subject to hand adjustment at all times and the quantity of air 120

125 130

and fuel is at all times under the regulation of the governor, without affecting the previously determined proportions.

What we claim and desire to secure by Letters Patent is:—

1. A mixing valve for explosive engines, having a continuously open and unobstructed fuel inlet, an outlet for the mixture in line with the fuel inlet, and separate air inlets on opposite sides of the fuel inlet, substantially as described.

2. A mixing valve for explosive engines, having a continuously open and unobstructed fuel inlet, an outlet for the mixture in line with the fuel inlet, and separate air inlets on opposite sides of the fuel inlet, and located between the fuel inlet and said outlet, substantially as described.

3. A mixing valve for explosive engines, having a continuously open and unobstructed fuel inlet, an outlet for the mixture in line with the fuel inlet, and separate air inlets on opposite sides of the fuel inlet and so arranged that a line connecting the centers of said air inlets is substantially perpendicular to a line connecting the centers of said outlet and fuel inlet, substantially as described.

4. In a mixing valve for explosive engines, the combination with the valve casing provided with a fuel inlet port, an outlet for the mixture opposite and in line with said inlet port, and air inlet ports arranged opposite to each other and on opposite sides of the fuel inlet port, a rotary and vertically movable valve in said casing provided with ports adapted to be brought into registration with the ports and apertures of the casing, a hand operated means for adjusting said valve in one of said directions and a governor for adjusting said valve in the other of said directions, substantially as described.

5. In a mixing valve for explosive engines, the combination with a cylindrical valve casing provided with a fuel inlet port, air inlet ports, and an outlet for the mixture and a removable head for closing one end of said casing, of a cylindrical valve fitting said casing and provided with apertures adapted to be brought into registration with the apertures in said casing, a valve rod extending through said valve, a removable securing device adjacent to said removable head, for securing the valve to the valve rod, whereby said head may be removed, and the valve removed from said rod and the valve casing; a governor connected to said rod, and a hand operated adjusting device detachably engaging said valve, substantially as described.

6. In a mixing valve for explosive engines, the combination with a cylindrical casing provided with a fuel inlet port, an outlet for the mixture opposite said inlet port, air inlet ports arranged on opposite sides of a

line connecting the fuel inlet and mixture outlet, of a cylindrical valve fitting said casing, and provided with apertures adapted to register with the apertures in said casing, a valve stem extending through said valve 70 casing and valve, and supporting said valve, a rotary hand operated device having a part located eccentrically with respect to said valve, and slidably engaging an aperture therein, for effecting the rotary adjustment 75 of said valve, substantially as described.

7. In a mixing valve for explosive engines, the combination with a cylindrical valve casing having a fuel inlet port, an outlet aperture for mixture opposite and in line 80 with said fuel inlet, and air inlet ports, disposed on opposite sides of a line connecting said fuel inlet port and said mixture outlet, a rotatable plate closing one end of said casing and a removable head closing the other 85 end of said casing, of a cylindrical valve fitting said casing and having apertures adapted to register with those of said casing a governor operated valve rod extending through said rotatable bottom plate and secured to said valve, a projection extending from said rotatable plate and having a sliding engagement with said valve eccentrically to said rod, means for rotating said plate, to effect the rotation of said valve in said 90 casing, and means for holding said plate in fixed relation with said valve casing, substantially as described.

8. In a mixing valve for explosive engines, the combination with the valve casing provided with an open and unobstructed fuel inlet port, an outlet for the mixture opposite and in line with said inlet port and separate air inlet ports located opposite to each other and on opposite sides of a line connecting the fuel inlet and mixture outlet ports, and means for adjusting the size of certain of said ports to vary the proportion of gas and air in the mixture, substantially as described.

9. In a mixing valve for explosive engines, the combination with the valve casing provided with an open and unobstructed fuel inlet port, an outlet for the mixture opposite and in line with said inlet port and separate air inlet ports located opposite to each other and on opposite sides of a line connecting the fuel inlet and mixture outlet ports, a movable valve in said casing provided with ports adapted to be brought into registration with the ports and apertures in said casing, and means for moving said valve in said casing to vary the size of certain of said ports, substantially as described.

10. In a mixing valve for explosive engines, the combination with the valve casing provided with an open and unobstructed fuel inlet port, an outlet for the mixture opposite and in line with said inlet port and separate air inlet ports located opposite to 130

each other and on opposite sides of a line connecting the fuel inlet and mixture outlet ports, a rotary cylindrical valve in said casing, provided with a gas inlet aperture 5 adapted to register with the gas inlet aperture of the casing, and having air apertures and a mixture outlet aperture larger than the respective apertures in the casing, and means for rotating said valve to vary the 10 amount of gas admitted without varying

the size of the air inlet or mixture outlet apertures, substantially as described.

In testimony whereof we affix our signatures, in the presence of two witnesses.
